WILLIAM PARKIN, OF TAUNTON, MASSACHUSETTS, ASSIGNOR TO
REED AND BARTON, OF SAME PLACE.

Design No. 3,440, dated March 30, 1869.

DESIGN FOR A FRUIT-TAZZA.

The Schedule referred to in these Letters Patent and making part of the same.

To all persons to whom these presents may come:

Be it known that I, WILLIAM PARKIN, of Taunton, in the county of Bristol, and State of Massachusetts, have invented or produced a "New Ornamental Design for a Preserve-Dish or Fruit-Tazza;" and do hereby declare the same to be fully represented in the accompanying drawing, which exhibits the design, in perspective, of the said article.

The drawing shows an oblong dish, A, having a flange, *a*, at and around its upper edge.

The said dish is rounded at its corners, and has straight sides and ends.

At each corner is a bracketed leg, B, surmounted by a mailed knight, C, carrying a shield and a staff.

On the top of the rim of the dish, and at the middle of each end, is a bust, D, of a female.

The handle, or bail E, is hinged to the dish at its middle, and is arched at top, and there surmounted by the figure of a greyhound, F, in a sitting posture.

I claim the said design, substantially as described and represented.

Witnesses: WILLIAM PARKIN.
